ATTORNEY

UNITED STATES PATENT OFFICE.

ALLEN E. OSTRANDER, OF RIDGEWOOD, NEW JERSEY, ASSIGNOR TO AMERICAN CAR AND FOUNDRY COMPANY, OF ST. LOUIS, MISSOURI, A CORPORATION OF NEW JERSEY.

ANCHOR FOR TANK-BANDS.

1,014,846.

Specification of Letters Patent.

Patented Jan. 16, 1912.

Application filed December 30, 1910. Serial No. 600,015.

To all whom it may concern:

Be it known that I, ALLEN E. OSTRANDER, residing at Ridgewood, Bergen county, New Jersey, and being a citizen of the United States, have invented certain new and useful Improvements in Anchors for Tank-Bands, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings, Figure 1 is a transverse sectional view through a tank car constructed in accordance with my invention, the tank being illustrated diagrammatically. Fig. 2 is a horizontal detail sectional view of the structure shown in Fig. 1, said section being taken on the line 2—2 of Fig. 1, and Fig. 3 is a side elevational view partly in section on line 3—3 of Fig. 1.

The object of this invention is to provide means attached to the cross bearer and to the center sills of the structure for attaching the opposite ends of the tank bands.

A further object is to provide a cross bearer of strong but light construction and to support upon the opposite ends of said cross bearer the running boards of the car.

With these and other objects in view, the invention comprises parts, referred to by numerals, as follows:

1—1 indicate the center sills; 2 the tank and 3 one of the tank bands which are usually employed in tank-car construction.

Fixed to the top flanges of the center sills is the tension member 4 of the cross bearer which extends beyond the opposite sides of said sills and carries upon the upper surface of its opposite ends the usual running boards as 5.

Extending beneath the under side of each of the center sills is a compression member 6 which is ordinarily of angle shape and is formed with a pendent flange as 7 and extends transversely of the car under said center sills. The portions of the member 6 extending laterally beyond said sills are bent upwardly as shown in Fig. 1 to engagement with the adjacent end portions of the ten-

sion member 4, where they are bent to a horizontal and are secured to said tension member as at 8.

Fixed to the under side of each of the center sills, adjacent the member 6 is an anchor casting 9 which casting is formed with a pendent flange 10 disposed to fit against the vertical leg of the angle 6 and to be riveted thereto. Each of said castings is also formed with an upwardly extending flange 11 disposed to engage the inner faces of the respective center sills and to be riveted thereto. Each of the castings 9 is further formed with an obliquely disposed extension 12 which is effectually strengthened by having one of its sides formed integral with the adjacent portion of the flange 10. The respective ends of the tank band are adapted to be passed through a suitable aperture as 13 formed in each of the extensions 12 and to be secured by a nut as 14 fixed to the end of said band below said flange.

With the structure as disclosed it is apparent that the strain of the tank bands is transferred partly to the center sills and partly to the cross bearer.

What I claim is:

1. In a tank car, a cross-bearer, center sills and tank band anchors connecting said sills and cross-bearers.

2. In a tank car, a cross-bearer and running board support, center sills and tank band anchors connecting said sills and cross-bearers.

3. In a tank car, a center sill, a cross-bearer extending partly below said center sill, tank band anchors connecting said sill and cross-bearer and tank bands terminating in said anchors.

4. In a tank car, a center sill, a cross-bearer and running board support extending partly below said center sill, tank band anchors connecting said sill and cross-bearer and tank bands terminating in said anchors.

5. In a tank car, center sills, a cross-bearer and tank band anchors connected respectively between and to said sills and to the cross-bearer.

6. In a tank car, flanged center sills, a flanged cross-bearer and flanged tank band anchors connected respectively with said sills and cross-bearer.

7. In a tank car, center sills, a cross-bearer comprising a member extending below said center sills and to a plane above

the bottom of said sills, anchor members connected with said member and to said sills and tank bands extending into said anchor members.

8. In a tank car, center sills, a cross-bearer comprising a flanged member, an anchor member formed with a flange adapted to engage the flange of the cross-bearer member, said anchor member serving as a connector between said cross-bearer member and said center sills and a tank band extending into said anchor member.

9. In a tank car, center sills, a cross-bearer comprising a flanged member, an anchor member formed with a flange adapt-

ed to engage the flange of the cross-bearer member, and being also formed with a plurality of flanges adapted to engage said center sills upon a plurality of faces, said anchor member serving as a connector between said cross-bearer member and said center sills and a tank band extending into said anchor member. 20

In witness whereof I have hereunto set my hand in the presence of two witnesses. 25

ALLEN E. OSTRANDER.
